UNITED STATES PATENT OFFICE

PETER FRÜH AND KARL BRAUN, OF GAUTING, NEAR MUNICH, GERMANY; SAID BRAUN ASSIGNOR TO SAID FRÜH

SPOOL FOR LOOMS AND OTHER TEXTILE MACHINES

Application filed October 3, 1927, Serial No. 223,614, and in Germany January 5, 1926.

We have filed applications in Germany, January 5, 1926, F. 60,648, VII, 86g, and August 17, 1926, F. 61,934.

5 Spools of light metal, for looms and other textile machines, have in some cases been provided with annular or helical, inwardly directed ribs, made by indentation, for engaging the spindles on which the spools are placed. These ribs are somewhat expensive to produce, and lack resilience, so that the spools are liable to bind on the spindles and can only be withdrawn with difficulty. Moreover, it is difficult so to produce them that uniform engagement with the spindle is obtained.

15 According to this invention these defects are overcome by making the ribs extend lengthwise of the spool. They are then resilient, and in producing the spool by a drawing process the ribs can readily be made 20 to conform to the taper of the spool, so that uniform contact with the spindle, throughout their length, is obtained. The flattenings due to the indentations give the yarn a better hold than it has on a spool which is circular 25 throughout, and the usual grooves provided to prevent the slipping off of the yarn may be dispensed with, or provided only at the edges of the depressions made by the indentations forming the ribs. The latter may have 30 slots, to increase their resilience, and tongues of metal may be bent inwards at their upper ends, to form abutments for the tip of the spindle.

Three embodiments of the invention are 35 shown in the accompanying drawing, in Figs. 1 and 2, Figs. 3 and 4 and Figs. 5 and 6 respectively; Figs. 1, 3 and 5 are vertical sections, and Figs. 2, 4 and 6 are cross-sections on the lines I—I, II—II and III—III respectively.

Referring first to Figs. 1 and 2, *a* is the 40 slightly tapered shank of the spool and *b* the foot thereof, these two parts being integral with each other, and being produced 45 by drawing a tubular blank of light metal. At the junction of the foot and shank there is a shoulder *c*. The shank has three inwardly directed, uniformly spaced vertical ribs *d* made by indenting, these ribs coming into 50 contact with the spindle, and exerting resili-

ent pressure, which enables the spool to be drawn off the spindle easily when required.

The shank may have external transverse grooves or shoulders *x* at the edges of the 55 grooves formed by the indentations made for producing the ribs *d*.

In the embodiment shown in Figs. 3 and 4 the shank *a*² has inwardly directed longitudinal ribs *d*¹, made by indentation, and at the upper end and the lower end of each rib a transverse slot *i* is made in the inwardly pressed portion of the metal, to increase the resilience of the ribs. At the upper ends of the ribs *d*¹ short tongues *k* of metal are bent 60 inwards from the parts where the slots are made, and these form abutments limiting the extent to which the spool can slip down the spindle. At their lower ends the ribs *d*¹ have enlargements *j*, which reduce the gaps between the ribs at this part, so that when the spool is slipped on to a spindle the tip of the spindle cannot enter the gap between two 65 ribs and become jammed.

In the modification shown in Figs. 5 and 6 70 the shank *a*² has longitudinal, inwardly directed ribs *d*², each of which has a slot *i*² extending lengthwise thereof, at its crest, the effect of these slots being to increase the resilience of the ribs. Where the ribs *d*² terminate at the bottom a short, thin tube *l* is inserted 75 into the spool, to guide the spool when it is slipped on to the spindle and prevent the tip of the spindle from becoming jammed between two ribs.

80 The ribs may be discontinuous, that is to say a series of short ribs *d*³, with gaps *y* between them, may be substituted for a single rib, and these shorter ribs may be placed out of direct alignment with each other.

85 What we claim as our invention and desire to secure by Letters Patent of the United States is:—

1. A bobbin of light metal, for textile machinery, having a foot and a tubular shank, 90 said shank having longitudinal, inwardly directed indentations forming ribs extending interiorly of the shank beyond its inner periphery, said ribs having slots extending lengthwise thereof.

2. A bobbin of light metal, for textile ma- 100

achinery, having a foot and a tubular shank, said shank having longitudinal, inwardly directed ribs formed by indentations, and said shank having also inwardly bent tongues of metal, one at the upper end of each rib.

5 3. A bobbin of light metal, for textile machinery, having a foot and a tubular shank, said shank having longitudinal, inwardly directed ribs formed by indentations, each of said ribs having lateral enlargements at its lower end.

10 4. A bobbin of light metal for textile machinery, comprising a foot and a tubular shank, said shank having integral therewith longitudinally extending inwardly directed imperforated reenforcing ribs of substantial length, adapted to yield under pressure.

15 In testimony whereof we hereunto affix our signatures.
